BOBBIN RECEIVER FOR WEFT
REPLENISHING LOOMS

Richard G. Turner, Worcester, Mass., assignor to
Crompton & Knowles Loom Works, Worcester,
Mass., a corporation of Massachusetts

Application December 22, 1945, Serial No. 636,944

26 Claims. (Cl. 139—255)

1

This invention relates to improvements in receivers for spent bobbins in weft replenishing looms and it is the general object of the invention to provide a simple and conveniently manipulated bobbin receiver including in its construction a flexible bobbin holding bag.

During the operation of weft replenishing looms spent or exhausted bobbins are expelled downwardly from the lay and must be collected in a receiver or the like to prevent scattering over the floor. It has been customary in the past to collect these bobbins in large unwieldy metal cans which have not only been expensive in construction but have been difficult to handle when being emptied of an accumulation of spent bobbins. It is an important object of my present invention to provide a simple form of supporting frame from which a bobbin receiving bag is suspended and mount the frame so that it can be readily removed and inverted by the attendant when the receiver is being emptied.

Weft replenishing looms ordinarily include in their construction the downwardly and forwardly directed bobbin chute along which the bobbins descend as they are expelled from the depleted shuttle. The bobbin receiver mouth must extend behind the forward limit of the path of movement of the chute to insure proper entry of the bobbins into the receiver. Because of this fact it is desirable to construct the receiver in such manner that it must first be moved forwardly clear of the path of the chute before it can be raised, and it is another object of my present invention to provide a pivotal support for the aforesaid frame around which the latter can be swung forwardly in advance of the path of the chute, after which the receiver can be removed from its support.

It is another object of my present invention to support the aforesaid frame in such manner that the weight of the bag and frame will be so disposed as to hold the receiver normally in bobbin receiving position. This result I accomplish by means of a stationary loom carried support having a stop bar to engage part of the aforesaid frame and hold the bobbin receiving mouth in normal position.

In order to prevent undesirable accidental forward movement of the receiver it is a further object of my invention to provide a form of yielding lock which will hold the framework in its normal rearward position. The lock not only assists gravity to hold the receiver in bobbin receiving position but also prevents upward movement of the receiver toward the path of the

2

chute until the receiver has been moved forwardly a safe distance.

When a flexible cloth bag of large bobbin holding capacity is used it is found that the bobbins cause it to bulge and project into the path of the picking mechanism which is ordinarily located immediately behind the bag. It is a further object of my present invention to provide a guard which keeps the back part of the bobbin bag from projecting into the path of operation of the picking mechanism. This guard may be either a part independent of the bag and held on the bag support, or it may be built into the bag in the form of a reinforcing stiff plate for the back wall of the bag.

When a cloth bag is inverted for the purpose of emptying it may be difficult to get all the bobbins out of the bag due to sagging of its bottom. It is another object of the present invention to provide reinforcements for the corners of the bag so that the latter will be braced against sagging when inverted.

With these and other objects in view which will appear as the description proceeds, my invention resides in the combination and arrangement of parts hereinafter described and set forth.

In the accompanying drawings, wherein two forms of my invention are set forth,

Fig. 1 is a front elevation of part of a loom, 30 showing the preferred form of the invention in normal position,

Fig. 2 is a side elevation looking in the direction of arrow 2, Fig. 1,

Fig. 3 is an enlarged horizontal section on line 3—3, Fig. 1,

Fig. 4 is a front elevation looking in the direction of arrow 4, Fig. 3, parts being omitted,

Fig. 5 is a vertical section on line 5—5, Fig. 4,

Fig. 6 is a plan view looking in the direction 40 of arrow 6, Fig. 1,

Fig. 7 is an enlarged vertical section on line 7—7, Fig. 6,

Figs. 8 and 9 are diagrammatic views showing the manner of handling the receiver when it is 45 to be emptied of bobbins,

Fig. 10 is a view similar to part of Fig. 2 showing the modified form of the invention, and

Fig. 11 is a horizontal section on line 11—11, 50 Fig. 10.

Referring to the drawings, the loom frame 10 supports a lay 11 provided with a shuttle box 12 from which depends a bobbin chute 13. During normal loom operation the lay reciprocates backwardly and forwardly and causes the chute to traverse a given path under the shuttle box.

Weft replenishing operations will ordinarily occur when the lay is at its foremost position or on so-called front center, at which time the spent or depleted bobbins will be expelled downwardly from the shuttle S and will be guided along the chute 13 in a generally forwardly and downwardly directed path. My present invention relates to improved preferably removable means for receiving and collecting the spent bobbins.

Referring more particularly to Figs. 1 and 2 the loom frame has projecting therefrom a support 15 secured to the loom frame as at 16 and having a horizontal bottom member 17 extending to the right away from the loom frame as viewed in Fig. 1 and formed with an upwardly opening recess 18. The member 17 has on the front side thereof an upwardly and forwardly flared lip or tongue 19 to provide the recess 18 with a widened mouth. Formed as part of the support 15 and located above the member 17 is a cross bar 20 extending horizontally and preferably parallel to the member 17. Right and left end guides 21 and 22 are formed on the support 15 adjacent to the ends of the recess 18 for a purpose to be described.

The bobbin receiver R comprises two main parts, the metallic frame F and the cloth bag B. The frame F may be formed of a long piece of tube bent to appropriate form to take the shape shown in Figs. 1 and 2. When so formed the frame will have vertical side members 25 and 26 located respectively at the right and left as viewed from the front of the loom and joined at their bottoms by a horizontal supporting member 27 integral with the side members. The upper ends of the side members 25 and 26 project rearwardly from the front of the receiver to form downwardly and backwardly inclined arms 30 and 31, respectively, the rear ends of which are preferably free. The side members are joined near their upper ends by a cross tube 32 secured to the members 25 and 26, and a second cross tube or bar 33 also secured to the members 25 and 26 is so located as to extend along and in front of the cross bar 20 of the support frame 15 when the parts are in the position shown in Fig. 2. The guides 21 and 22 position the side members 25 and 26, respectively, to locate the frame as shown in Fig. 1. Additional forwardly extending guides 23 on support 15 may be provided to brace the side members above the guides 21 and 22.

The bag B may be made of suitable durable fabric and has right and left sides 35 and 36, a back wall 31 and a front wall 38. These walls are connected at their bottoms to a flat strip of sheet material serving as a floor 39 for the bag. The floor may be cemented or otherwise secured to the several walls of the bag.

The tops of the right and left walls 35 and 36 are provided with hems 40 through which are slipped the arms 30 and 31. The front wall 38 is provided with eyelets and grommets 42 through which extend attaching cords 43 wrapped around the members 25 and 26 preferably below the upper cross bar 32 and then knotted. The outer wall 35 and front wall 38 adjacent the forward right end of the bag are provided with a pair of grommets 45 through which extends a short flexible cord 46 tied around vertical side member 25 under cross bar 33. In similar manner the inner or left wall 36 and front wall 38 are provided with grommets 47 through which extends another flexible cord 48 tied around side member 26 under cross bar 33.

A yielding lock designated generally at 50 is

formed of resilient sheet material and is secured at 51 to the cross bar 20 of frame 15. This lock has upper and lower prongs 52 and 53 the forward free ends of which are shaped as indicated in Fig. 5 so that cross bar 33 will normally lie between the prongs 52 and 53 but can pass between the free ends of the prongs when moving forwardly or backwardly. While I have shown two of these prongs, it should be borne in mind that the bottom prong 53 can be omitted, but the upper prong is desirable for a reason which will appear presently. Whatever specific form the yielding lock 50 takes it should have some resilience and should preferably extend over and in contact with a cross bar 33 when frame F is seated in the recess 18 as shown in Fig. 2.

Under normal conditions the receiver will be in the position shown in Figs. 1 and 2 and the upwardly facing mouth of the bag designated at M will be positioned to receive bobbins B' as they descend along the chute 13 incident to replenishing operations of the loom. When it is desired to empty the bag of its accumulation of spent bobbins, the attendant will grasp the cross tube or bar 32 with one hand and rock the frame and bag forwardly or to the left as viewed in Fig. 8 during which operation the support member 27 of the frame F will rock in the recess 18 as by a pivotal action. After the frame has been moved forwardly from the position of Fig. 2 to that shown in Fig. 8 the cross bar 33 will be in front of the upper prong 52, the frame may then be lifted entirely free of the support 15 to the position indicated in Fig. 9. The attendant will then grasp either the bar 33 or the cross member 27 with his other hand and invert the bag for the purpose of emptying the bobbins into a box or the like not shown moved from loom to loom for the purpose. During this emptying operation the cords 46 and 48 due to their support by the cross bar 33 will hold the bag against collapsing and will permit the bobbins to move out of the mouth of the bag when the latter is inverted. Bar 27 is then reinserted into the recess 18 and the receiver swung rearwardly so that cross bar 33 will pass under the top resilient prong 52 and be held by it against the cross bar 20.

It will be apparent from Fig. 2 that when the receiver is in normal position the greater part of its weight is behind the cross bar 20 and the receiver therefore tends to remain in position with the support member 27 in recess 18, bar 33 against bar 20, and lateral movement is prevented by stops 21 and 22. Furthermore, cross bar 33 is held against the bar 20 by the prong 52.

In order to insure proper entry of the bobbins into the bag the mouth M must project behind the forward part of the path traversed by the chute. Because of this fact damage might result if the receiver were lifted straight up from the position shown in Fig. 2. To prevent such movement the upper prong 52 is made long enough to require the frame F to be swung forwardly to a position where all parts of the receiver will be forward of said path before the receiver can be raised. The upper part of the back wall of the bag extends freely between the arms 30 and 31 and is flexible so that it will not be damaged if accidentally struck by the chute. The center around which the receiver is swung is low enough so that when the arms 30 and 31 swing forwardly their upward motion will be along arcs below the path of the bobbin chute.

As previously mentioned the cloth bag tends to bulge at the bottom thereof due to the weight of the bobbins in it. The picker mechanism indi-

cated by the picker stick **P** lies immediately behind the bag already described and causes the stick to move along a given path during its shuttle picking stroke. In order to prevent interference between the picking mechanism and the bag I provide a guard **60** having a foot **61** secured as at **62** to the under side of the support **15**. The foot extends rearwardly and joins a vertical guard wall **63** which lies immediately behind the back wall of the bag and is spaced forwardly from the picker mechanism. The wall **63** is of sufficient width to keep all parts of the bag from moving into the path of the picker mechanism. This path is indicated by the dot and dash line **a** in Fig. 11.

In the preferred form of the invention already described the flexibility of the bag makes desirable the use of guard **60**. I do not wish, however, to be limited to the use of the guard shown in Fig. 2, since it is possible to build the guard into the bag as shown in the modified form of the invention set forth in Figs. 10 and 11. In this modified form of receiver the bag **65** has built into it a flat plate **66** which is secured to the side walls **67** and **68** of the bag **65** as indicated at **69** in Fig. 11. Plate **66** extends upwardly a sufficient distance to protect the bag from the picker mechanism and in effect serves the same function as the guard wall **63**.

It is desirable that some form of reinforcement be provided to keep the bag from sagging out of shape when being turned horizontally and then vertically during the emptying operation. The rear parts of the bag will be reinforced by the aforesaid plate **66**, but in order to reinforce the front of the bag I provide two vertical rods **70**, one for each of the front corners of the bag as shown more particularly in Fig. 11. These rods **70** are held in the front corners of the bag by stitching **71** and extend for the greater part of the height of the bag along the vertical members **25** and **26** and in position to engage the cross bars joining these members when the bag is turned to a horizontal position during the emptying operation. It will be obvious that when the guard wall **63** is used reinforcing wires or rods similar to those shown at **70** can be employed for the back corners of the bag to take the place of the reinforcement provided by the plate **66**.

From the foregoing it will be seen that I have provided a simple form of bobbin receiver wherein the frame **F** supports the bobbin receiving bag **B** in bobbin receiving position. The receiver is, however, readily removable from the support **15** when the bag is to be emptied of bobbins. It will also be seen that the side members **25** and **26** extend vertically and are forward of the center of gravity of the receiver as a whole and for this reason the receiver tends by its weight to remain in the position shown in Fig. 2. Furthermore, the resilient prong **52** not only serves as a resilient lock to hold the receiver in normal position but also resists upward movement of the receiver until the receiver is forward of the path traversed by the chute **13**. It will also be noted that the bag is attached to the frame **F** by cords **46** and **48** in such manner as to be held against collapsing when inverted for the purpose of emptying bobbins. The hem **40** tend by gravity to slide down the arms **30** and **31** and keep the mouth of the bag open. The guards **60** and **66** keep the bag from bulging rearwardly into the path of the picker mechanism, and the reinforcing rods **70** prevent sagging of the bag when it is inverted.

Having thus described my invention it will be seen that changes and modifications may be made

therein by those skilled in the art without departing from the spirit and scope of the invention and I do not wish to be limited to the details herein disclosed, but what I claim is:

- 5 1. In a weft replenishing loom from which depleted bobbins are discharged, a bobbin receiver for said bobbins, a support secured to the loom, a frame mounted on the support and extending upwardly therefrom, a bobbin receiving bag suspended from the upper part of said frame and hanging downwardly therealong, and means to resist swaying of the lower part of the bag during loom operation.
- 10 2. In a weft replenishing loom from which depleted bobbins are discharged, a bobbin receiver for said bobbins, a support fixed to the lower part of the loom, a frame mounted on said support and extending upwardly therefrom, a bobbin receiving flexible bag supported at the upper end thereof to said frame and extending downwardly therealong, and means connecting the lower part of the bag to said frame to resist swaying of said bag during loom operation.
- 15 3. In a weft replenishing loom having a bobbin discharging chute traversing a given back and forth path, a support secured to the lower part of the loom, a bobbin receiver having a bobbin receiving mouth normally extending under the forward part of said path, and means constituting a horizontal pivotal connection between the support and the lower part of the receiver around which the upper part of the receiver is movable forwardly to a position in which said mouth is forward of said path.
- 20 4. In a weft replenishing loom having a bobbin discharging chute traversing a given back and forth path, a support secured to the loom, a bobbin receiver having a mouth normally extending under the forward part of said path, said support and receiver having cooperating parts forming a pivotal mounting around which the receiver is movable forwardly and said pivotal mounting permitting upward movement of the receiver, and a guard on said support overhanging part of said receiver, said guard overhanging said part during forward pivotal movement of the receiver to prevent upward movement of the receiver until the mouth of the latter is forward of said path.
- 25 5. In a weft replenishing loom having a bobbin discharging chute traversing a given back and forth path, a support secured to the loom having an upwardly opening recess therein, a bobbin receiver mounted on said support and having a part thereof entering said recess and defining with the latter a pivotal connection between the receiver and support around which said receiver is movable pivotally in a forward direction, said pivotal connection permitting upward movement
- 30 6. In a weft replenishing loom having a bobbin discharging chute traversing a given back and forth path, a support secured to the loom in fixed position with respect to said path, a bobbin receiver, the lower part thereof and said support cooperating to mount the receiver for forward pivotal movement of the upper part of the receiver from normal position
- 35 7. In a weft replenishing loom having a bobbin discharging chute traversing a given back and forth path, a support secured to the lower part of the loom in fixed position with respect to said path, a bobbin receiver, the lower part thereof and said support cooperating to mount the receiver for forward pivotal movement of the upper part of the receiver from normal position
- 40 8. In a weft replenishing loom having a bobbin discharging chute traversing a given back and forth path, a support secured to the lower part of the loom in fixed position with respect to said path, a bobbin receiver, the lower part thereof and said support cooperating to mount the receiver for forward pivotal movement of the upper part of the receiver from normal position
- 45 9. In a weft replenishing loom having a bobbin discharging chute traversing a given back and forth path, a support secured to the lower part of the loom in fixed position with respect to said path, a bobbin receiver, the lower part thereof and said support cooperating to mount the receiver for forward pivotal movement of the upper part of the receiver from normal position
- 50 10. In a weft replenishing loom having a bobbin discharging chute traversing a given back and forth path, a support secured to the lower part of the loom in fixed position with respect to said path, a bobbin receiver, the lower part thereof and said support cooperating to mount the receiver for forward pivotal movement of the upper part of the receiver from normal position
- 55 11. In a weft replenishing loom having a bobbin discharging chute traversing a given back and forth path, a support secured to the lower part of the loom in fixed position with respect to said path, a bobbin receiver, the lower part thereof and said support cooperating to mount the receiver for forward pivotal movement of the upper part of the receiver from normal position
- 60 12. In a weft replenishing loom having a bobbin discharging chute traversing a given back and forth path, a support secured to the lower part of the loom in fixed position with respect to said path, a bobbin receiver, the lower part thereof and said support cooperating to mount the receiver for forward pivotal movement of the upper part of the receiver from normal position
- 65 13. In a weft replenishing loom having a bobbin discharging chute traversing a given back and forth path, a support secured to the lower part of the loom in fixed position with respect to said path, a bobbin receiver, the lower part thereof and said support cooperating to mount the receiver for forward pivotal movement of the upper part of the receiver from normal position
- 70 14. In a weft replenishing loom having a bobbin discharging chute traversing a given back and forth path, a support secured to the lower part of the loom in fixed position with respect to said path, a bobbin receiver, the lower part thereof and said support cooperating to mount the receiver for forward pivotal movement of the upper part of the receiver from normal position
- 75 15. In a weft replenishing loom having a bobbin discharging chute traversing a given back and forth path, a support secured to the lower part of the loom in fixed position with respect to said path, a bobbin receiver, the lower part thereof and said support cooperating to mount the receiver for forward pivotal movement of the upper part of the receiver from normal position

thereof, said receiver being so disposed when in normal position that the center of gravity thereof tends to move said receiver toward said path, and stop means on said support engaging said receiver to limit rearward movement thereof.

7. In a weft replenishing loom having a bobbin discharging chute traversing a given back and forth path, a support secured to the loom in fixed position with respect to said path, a bobbin receiver having a part thereof mounted on said support for movement of the receiver forwardly from the normal position thereof, said receiver being so disposed when in normal position that the center of gravity thereof tends to move said receiver toward said path, stop means on said support engaging said receiver to limit rearward movement thereof, and resilient means on said support normally engaging said receiver and tending to hold the latter in position to engage said stop means.

8. In a weft replenishing loom having a bobbin discharging chute traversing a given back and forth path, a stationary support fixed to the loom, a bobbin receiver having a mouth extending under a part of said path, means on said receiver and support constituting a pivotal mounting around which said receiver is movable forwardly, and a yielding guard on said support overhanging a part of said receiver and tending normally to hold said receiver in normal position and effective during forward pivotal movement of the receiver to overhang said part until after said mouth has moved to a position forward of said path.

9. In a weft replenishing loom, a support fixed with respect to the loom, a bobbin receiver mounted on said support for forward and upward movement relatively to said support, and a combined guard and yielding lock means mounted on said support and overhanging a part of said receiver and tending normally to hold the receiver in bobbin receiving position, said means preventing upward movement of said receiver until the latter during forward movement thereof causes said part to move forward of said combined guard and yielding lock means.

10. A bobbin receiver for a weft replenishing loom having horizontally spaced side members each formed with an arm extending rearwardly from the front of the receiver, means connecting said side members, and a bobbin receiving bag supported by said arms and attached to said side members.

11. A bobbin receiver for a weft replenishing loom including a frame having a substantially horizontal part from each end of which a side member extends upwardly and then rearwardly from the front of the receiver to form a supporting arm, and a bobbin receiving bag supported by said arms and attached to said side members.

12. A bobbin receiver for a weft replenishing loom, said receiver comprising a frame at the front thereof comprising a substantially horizontal bottom member, a side member integral with and extending upwardly from each end of said bottom member, an arm integral with and extending from each side member rearwardly from the front of the receiver, and a bobbin receiving bag supported by said arms and attached to said side members.

13. In a bobbin receiver for a weft replenishing loom, a frame at the front of the receiver comprising a substantially horizontal bottom member, a side member extending upwardly from each end of said bottom member, an arm for

the upper part of each side member extending rearwardly from the front of the receiver, a bag suspended from the arms, cross bar means connecting said side members, and attaching means for the bag passing around said side members and under said cross bar means.

14. In a bobbin receiver for a weft replenishing loom, a frame at the front of the receiver having a substantially horizontal bottom member connected at each end thereof to an upwardly extending side member from which an arm extends downwardly and rearwardly from the front of the receiver, a bag suspended from said arms, a cross bar extending between said side members adjacent to the bottom member, a second cross bar extending between said members adjacent said arms, and means attaching said bag to said frame including holding elements located adjacent the bottom of the bag and passing under the first named cross bar and other holding elements located adjacent the top of the bag and passing under the second named cross bar.

15. In a bobbin receiver for a weft replenishing loom, a substantially horizontal bottom member, a side member extending upwardly along the front of the receiver, from each end of the bottom member, an arm extending rearwardly from each side member, a bobbin receiving bag suspended from said arms and located rearwardly of said side members, and means attaching the forward part of said bag to the upper and lower parts of said side members.

16. A bobbin receiver for a weft replenishing loom provided with a support having a guard thereon, said receiver comprising a substantially horizontal bottom member formed for mounting on said support, a side member extending upwardly from each end of said bottom member, a rearwardly extending arm on each side member, a cross bar adjacent to said bottom member extending between said side members for engagement with said guard, and a bobbin receiving bag suspended from said arms and having the lower part thereof attached to said cross bar.

17. A bobbin receiver for a weft replenishing loom, said receiver comprising a frame at the front thereof having a substantially horizontal bottom member, an upwardly extending side member connected to each end of the bottom member, a rearwardly extending arm on each side member, a cross bar connecting said side members adjacent said arms and affording a hand hold for manipulation of the receiver, and a bobbin receiving bag supported by said arms, and means on said bag engaging said side members below said cross bar to limit rearward movement of the bag relatively to said side members.

18. In a bobbin receiver for a weft replenishing loom, the front part of said receiver comprising side members, an arm extending rearwardly from the upper end of each side member, a cross bar connecting the lower ends of said side members and affording a hand hold, a second cross bar connecting the upper parts of said side members and affording a second hand hold, a bag suspended from said arms and having forward parts thereof extending downwardly along said side members, and attaching means for the bag passing under said cross bars, the cross bars affording means for inverting the receiver for the emptying of bobbins therefrom.

19. In a bobbin receiver for a weft replenishing loom, a frame having spaced vertical members at the front of the receiver, an arm extending rearwardly and downwardly from the upper

end of each member, a cloth bobbin holding bag having the forward part thereof connected to said vertical members and having a bobbin receiving mouth between said arms, and means attaching the top of the bag to said arms, said attaching means tending by gravity to move down said arms to keep the bobbin receiving mouth open.

20. In a weft replenishing loom having shuttle picking mechanism moving along a given path, a bobbin receiver for bobbins discharged during weft replenishing operations of the loom located in front of said path, said receiver having flexible side and front walls, and means forming part of the receiver extending along the back thereof between the side walls to prevent the receiver from bulging into said path of the picking mechanism.

21. In a bobbin receiver for a weft replenishing loom having picking mechanism moving in a given path, said receiver including a flexible bag provided with a rigid rear wall which faces said path when the receiver is in bobbin receiving position.

22. A bobbin receiver for a weft replenishing loom, said receiver including a frame having horizontally spaced substantially vertical side members connected together and having their upper ends extended rearwardly from the front of the receiver, a flexible bobbin bag supported by said rearwardly extending upper ends of the side members, and means connecting the lower parts of the bag and frame limiting rearward movement of the bag relatively to the side members.

23. A bobbin receiver for a weft replenishing loom, said receiver including a frame having a cross bottom member and side members extending upwardly from the bottom member and having the upper parts thereof extended rearwardly from the front of the receiver, a flexible bobbin bag supported by the rearwardly extended upper parts of said side members, and means connect-

ing the lower parts of the frame and bag limiting movement of the bottom of the bag rearwardly from said side members.

24. A bobbin receiver for a weft replenishing loom having a lay and a support, said receiver including a frame having horizontally spaced substantially vertical side members the upper ends of which are extended rearwardly toward the lay, a flexible bobbin bag supported by said rearwardly extended upper ends, means connecting the lower parts of the bag and side members limiting rearward movement of the bag relatively to the frame toward the lay, and means connecting said side members to engage said support to hold the receiver in operative position on the loom.

25. A bobbin receiver for a weft replenishing loom having a lay and a support, said receiver including a frame having horizontally spaced substantially vertical side members connected together and having the upper ends thereof extended rearwardly toward the lay, a flexible bobbin bag supported by said rearwardly extended upper ends, means on the bag engaging the lower part of the frame limiting rearward movement of the bag relatively to the frame toward the lay, and means secured to said frame to engage said support to hold the receiver in operative position on the loom.

26. A bobbin receiver for a weft replenishing loom, said receiver including a flexible bag the upper end of which has a substantially rectangular bobbin receiving mouth, a frame having substantially vertical side members extending along the bag and having their upper ends extended along opposite sides of the mouth, means by which the bag is supported by said upper ends, and means connecting the lower ends of the bag and frame to limit movement of the bottom of the bag away from the side members.

RICHARD G. TURNER.
